UNITED STATES PATENT OFFICE.

CHARLES J. THATCHER, OF NEW YORK, N. Y.

PROCESS OF PRODUCING PARAMIDOPHENOL AND ITS COMPOUNDS.

No Drawing.

Application filed January 24, 1920. Serial No. 353,742.

To all whom it may concern:

Be it known that I, CHARLES J. THATCHER, a citizen of the United States, and a resident of New York city, in the county of New York and State of New York, have invented certain new and useful Improvements in the Processes of Producing Paramidophenol and Its Compounds, of which the following is a specification.

10 The invention relates to a process for producing paramidophenol base and its salts such as the sulfate $(C_6H_4NH_2OH)_2H_2SO_4$, more particularly by the electrolytic reduction of nitrobenzol in sulfuric acid. It has 15 for its object to readily and economically produce, on a commercial scale, paramidophenol base and its salts in a pure condition, and, particularly in the case of the salts such as the sulfate, of a white color. To this end, 20 the process consists of the following steps:

I. Nitrobenzol, preferably redistilled, is mixed with or dissolved in sulfuric acid partly diluted to give a content of about 78%. Preferably, brimstone acid free from 25 metals is used, a good proportion of acid to nitrobenzol being approximately ten to one; and a convenient quantity for electrolysis in a single cell is 125 pounds sulfuric acid to 14 pounds of nitrobenzol. This mixture is 30 designed to be reduced in the cathode compartment of a suitable diaphragm cell of any well-known or special construction, for example a cell such as is set forth in my pending application Serial No. 332,228, filed Oct. 21, 1919. A carbon or other suitable cathode may be employed, and the current density is maintained at substantially three amperes per square decimeter of electrode surface. The voltage drop thru the 35 cell should not be greater than about four volts, the amperage being regulated accordingly, and increased with increase of temperature, as the latter is accompanied by a corresponding decrease in the internal resistance of the cell, resulting in decreased 40 electromotive force.

It will be found that with a suitable cell, a temperature of 70° to 80° C. is attained, which latter temperature, however, should 45 not be much exceeded. It is desirable to start with a warm or hot mixture of sulfuric acid, which is conveniently prepared by diluting 1.84 specific gravity oil of vitriol to the specified strength, just or shortly before 50 starting the electrolysis. The nitrobenzol is best added gradually rather than by in-

roducing the full quantity at the start; and it is desirable to keep an excess of nitrobenzol in the electrolyte which has not been completely reduced. The anolyte should 55 consist of 50% to 55% sulfuric acid having anodes consisting preferably of chemical lead sheets; and, since the anolyte increases in strength as the electrolysis proceeds, the same is to be corrected from time to time by 60 withdrawing a small portion thereof and replacing with the proper quantity of water.

To reduce the 14 pounds of nitrobenzol aforesaid, about 6000 ampere hours are required, and vigorous and continued stirring 65 is highly desirable.

II. At the conclusion of the electrolysis, after substantially complete reduction of the nitrobenzol, the hot reduced liquor should be immediately withdrawn from the cell and 70 allowed to cool gradually to a temperature of 20° C. or less, which operation may require several days. The cooled liquor crystallizes and has the appearance of being 75 solid; but, upon stirring, acquires a semi-liquid state, consisting of crystals and liquor.

III. After having cooled, the liquor is separated from the crude crystals, consisting principally of paramidophenol sulfate, as by 80 filtering same, preferably with suction. This more or less complete separation of the liquor from the crude crystals is desirable in order to obtain a substantially pure product, since neutralization of the bulk of sulfuric acid, together with the crude crystals of paramidophenol sulfate, makes subsequent 85 purification impracticable. The filtration may require a day or more, and should be continued until all the liquor has been removed for the crystals, which then have a bluish white appearane. At this stage, it is advisable, also, to wash them with more or less concentrated sulfuric acid until substantially white.

IV. The crystals still contain several 90 times their weight of sulfuric acid, which excess of acid must be neutralized. This may be readily accomplished by dissolving the crude crystals in water and adding gradually, with stirring, thin, strained milk of lime, until the liquid is substantially neutral to Congo red test paper. In order to prevent oxidation or to reduce oxidized 95 compounds, a little sulfite, or bisulfite, of soda should be added during the neutralization before its completion, or at least at 100 105 110

some later stage of the process preceding crystallization of the final product.

5 V. The liquor becomes hot during this neutralization and should be filtered off, preferably before cooling, from the precipitated lime sludge (CaSO_4).

10 VI. The latter is washed six or seven times, the washings being kept separate for washing the next neutralization, each portion being advanced so that the seventh washing, which starts with pure water, will be the sixth washing on the next neutralization, and so on.

15 VII. To prepare the sulfate, the filtrate from the lime sludge, obtained as set forth in step V, and the first washing may now be evaporated, preferably in a vacuum evaporator or an open lead pan, until it crystallizes on cooling, adding a suitable 20 quantity of sodium sulfite or bisulfite toward the end of the evaporation and correcting the acidity so that the liquor remains neutral to Congo red test paper.

25 If the base, or some salt of paramidophenol other than the sulfate, be desired, this is effected by further neutralizing the liquor, obtained as set forth in step V, preferably with carbonate of lime, which, when cool, gives a mixed precipitate of calcium sulfate and of paramidophenol base. The carbonate of lime is added to the more or less dilute solution until there is no more effervescence. The mixed precipitate is then filtered off, and the paramidophenol base 30 can be separated from the calcium sulfate by leaching out with very hot water, the base crystallizing out again on cooling. The same quantity of water may be used for a second and, if necessary, other extractions. 35 The base so prepared may be filtered off and dried.

40 Or, if a salt is desired, the base is mixed with a suitable quantity, say ten times as much, water, and the acid whose salt is to be prepared is then added with heating until the resulting solution is neutral to Congo red test paper. It is then crystallized by cooling or evaporating, as may be necessary. The hydrochloride, for example, 45 may thus be prepared by the addition of hydrochloric acid; or other salts, such as the acetate, can be thus obtained by adding the corresponding acid.

45 The liquor resulting from the first crystallization may be evaporated and crystallized time after time until the resulting crystals become impure, at which time the precipitation of base is carried out just as above described, and the filtrate discarded. 55 It has been my practice to add the final mixed precipitate of calcium sulfate and base to the crude crystals before they are neutralized with lime, as set forth in step IV.

60 VIII. In all cases where pure, white com-

pounds are desired, the evaporated liquor, obtained as set forth in step VII, should be treated with animal charcoal, while hot, to remove coloring matter.

65 IX. It should then be cooled to about 70 35° C . and filtered at or about this temperature to remove other impurities.

X. After the filtration is completed, the liquor is further cooled, preferably slowly and to a substantial degree, until it crystallizes.

75 XI. The supernatent liquor is then filtered off or drawn off, and the crystals are centrifuged until nearly dry.

80 XII. They may then be finally dried; or, treated, if desired, while moist, with pure methyl alcohol to provide a methylated paramidophenol sulfate, and then dried, preferably in a vacuum drier, resulting in a pure, white paramidophenol sulfate or 85 methylated paramidophenol sulfate.

90 The methylating of the sulfate to produce methylated paramidophenol sulfate is effected best by pouring wood alcohol over the crystals after as much liquor as is possible has been centrifuged off and while the crystals are still moist. The wood alcohol, either by a chemical or physical action, breaks down the crystals more or less, forming a very fine, white powder when dry.

95 The highest degree of purity may, furthermore, be obtained by recrystallizing the paramidophenol sulfate several times from water containing animal charcoal and sodium bisulfite.

100 I claim:

105 1. In the manufacture of paramidophenol and its compounds, the process of reducing nitrobenzol by electrolyzing the same in sulfuric acid, diluted to a content not exceeding about 78%, until the liquor will crystallize when cooled, cooling to crystallize the liquor, filtering off the mother liquor, dissolving the crystals in water, and neutralizing the excess acid thereof, whereby 110 a paramidophenol compound readily soluble in water is obtained.

115 2. In the manufacture of paramidophenol and its compounds, the process of reducing nitrobenzol by electrolyzing the same in sulfuric acid, diluted to a content not exceeding about 78%, until the liquor will crystallize when cooled, cooling to crystallize the liquor, filtering off the mother liquor, dissolving the crystals in water, neutralizing the excess acid thereof, and introducing a sulfite.

120 125 3. The process of manufacturing, electrolytically, paramidophenol sulfate, which consists in electrolyzing nitrobenzol in sulfuric acid, diluted to a content not exceeding about 78%, until the liquor will crystallize when cooled, cooling to crystallize the liquor, filtering off the mother liquor, dissolving the crystals in water and neutralizing 130

the excess acid thereof, introducing a sulfite, evaporating, crystallizing and separating the crystals, and drying the same.

4. The process of manufacturing, electrolytically, paramidophenol sulfate, which consists in reducing nitrobenzol by electrolyzing the same in a cathode compartment with sulfuric acid substantially in the proportion of 14 parts of the former to 125 parts of the latter, which is of a concentration of about 78% sulfuric acid, at a temperature of substantially 75° C. and a current density of substantially three amperes per square decimeter of cathode surface, until the liquor will crystallize when cooled, cooling to crystallize the liquor, filtering off the mother liquor, dissolving the crystals in water, neutralizing the excess acid thereof, introducing a sulfite, evaporating, crystallizing, separating the crystals, and drying the same.

5. The process of manufacturing, electrolytically, paramidophenol sulfate, which consists in reducing nitrobenzol by electrolyzing the same in a cathode compartment with sulfuric acid substantially in the proportion of 14 parts of the former to 125 parts of the latter, which is of a concentration of about 78% sulfuric acid, at a temperature of substantially 75° C. and a current density of substantially three amperes per square decimeter of cathode surface until the liquor will crystallize when cooled, cooling to crystallize the liquor, filtering off the mother liquor, washing with sulfuric acid, dissolving the crystals in water, neutralizing the excess acid thereof, introducing a sulfite, evaporating, crystallizing, separating the crystals, and drying the same.

6. The process of manufacturing, electrolytically, paramidophenol sulfate, which consists in reducing nitrobenzol by electrolyzing the same in a cathode compartment with sulfuric acid substantially in the proportion of 14 parts of the former to 125 parts of the latter, which is of a concentration of about 78% sulfuric acid, at a temperature of substantially 75° C. and a current density of substantially three amperes per square decimeter of cathode surface until the liquor will crystallize when cooled, cooling to crystallize the liquor, filtering off the mother liquor, washing with sulfuric acid, dissolving the crystals in water, neutralizing the excess acid thereof with calcium hydrate, introducing a sulfite, evaporating, crystallizing, separating the crystals, and drying the same.

7. The process of manufacturing, electrolytically, paramidophenol sulfate, which consists in reducing nitrobenzol by electrolyzing the same in a cathode compartment with sulfuric acid substantially in the proportion of 14 parts of the former to 125 parts of the latter, which is of a concentra-

tion of about 78% sulfuric acid, at a temperature of substantially 75° C. and a current density of substantially three amperes per square decimeter of cathode surface until the liquor will crystallize when cooled, cooling to crystallize the liquor, filtering off the mother liquor and washing the crystals with sulfuric acid, dissolving the crystals in water, neutralizing the excess sulfuric acid by adding milk of lime until the liquor is neutral to Congo red test paper and introducing a sulfite, filtering off the liquor from the precipitated lime sludge and washing the latter a number of times with water, evaporating the filtrate until it crystallizes when cooled and correcting for acidity, treating with animal charcoal and filtering at about 35° C., cooling the liquor to crystallize same, withdrawing the mother liquor, and finally thoroughly drying the crystals.

8. The process of manufacturing, electrolytically, paramidophenol sulfate, which consists in reducing nitrobenzol by electrolyzing same in sulfuric acid until the liquor will crystallize when cooled, cooling to crystallize the liquor, filtering off the mother liquor, dissolving the crystals in water and neutralizing the excess acid thereof with calcium hydrate, introducing a sulfite, filtering, evaporating, crystallizing and separating the crystals, drying the same, and recrystallizing.

9. The process of manufacturing, electrolytically, paramidophenol sulfate, which consists in reducing nitrobenzol by electrolyzing same in sulfuric acid until the liquor will crystallize when cooled, cooling to crystallize the liquor, filtering off the mother liquor, dissolving the crystals in water and neutralizing the excess acid thereof, introducing a sulfite, filtering, evaporating, crystallizing and separating the crystals, treating with methyl alcohol, and drying.

10. The process of manufacturing, electrolytically, paramidophenol sulfite, which consists in reducing nitrobenzol by electrolyzing same in sulfuric acid until the liquor will crystallize when cooled, cooling to crystallize the liquor, filtering off the mother liquor, dissolving the crystals in water and neutralizing the excess acid thereof, introducing a sulfite, filtering, evaporating, crystallizing and separating the crystals, partly drying the crystals, treating with methyl alcohol, and further drying.

11. The herein-described product consisting of paramidophenol sulfate in the form of a dry white powder.

12. In the manufacture of paramidophenol and its compounds, the process of reducing nitrobenzol by electrolyzing the same in sulfuric acid until the liquor will crystallize when cooled, cooling to crystallize the liquor, filtering off the mother

liquor, dissolving the crystals in water, neutralizing the excess acid thereof, introducing a sulfite, filtering, further neutralizing with calcium hydrate, filtering off the precipitate and separating the paramidophenol base.

13. In the manufacture of paramidophenol and its compounds, the process of reducing nitrobenzol by electrolyzing the same in sulfuric acid until the liquor will crystallize when cooled, cooling to crystallize the liquor, filtering off the mother liquor, dissolving the crystals in water, neutralizing the excess acid thereof, introducing a sulfite, filtering further neutralizing with calcium carbonate, filtering off the precipitate and separating the paramidophenol base by leaching out with hot water, cooling to crystallize the base, filtering, and drying.
14. In the manufacture of paramidophenol and its compounds, the process of reducing nitrobenzol by electrolyzing the same in sulfuric acid until the liquor will crystallize when cooled, cooling to crystallize the liquor, filtering off the mother liquor, dissolving the crystals in water, neutralizing the excess acid thereof, introducing a sulfite, filtering further neutralizing with

calcium carbonate, filtering off the precipitate and separating the paramidophenol base by leaching with hot water, cooling to crystallize the base, filtering, redissolving by adding an acid to form a paramidophenol salt.

15. In the manufacture of paramidophenol and its compounds, the process of reducing nitrobenzol by electrolyzing the same in sulfuric acid until the liquor will crystallize when cooled, cooling to crystallize the liquor, filtering off the mother liquor, dissolving the crystals in water, neutralizing the excess acid thereof, introducing a sulfite, filtering, further neutralizing with calcium carbonate, filtering off the precipitate and separating the paramidophenol base by leaching with hot water, cooling to crystallize the base, filtering, adding an acid with heating and until the resulting solution is neutral to Congo red test paper, and then evaporating to crystallization.

Signed at New York, in the county of New York and State of New York, this 23rd day of January A. D. 1920.

CHARLES J. THATCHER.
